CLAIM

We claim the ornamental design for a submersible pump housing, as shown and described.

DESCRIPTION

FIG. 1 is a perspective view of a submersible pump housing showing our new design;

FIG. 2 is one side elevational view;

FIG. 3 is a side elevational view rotated 90° from the position shown in FIG. 2;

FIG. 4 is a side elevational view rotated 90° from the position shown in FIG. 3;

FIG. 5 is a side elevational view rotated 90° from the position shown in FIG. 4;

FIG. 6 is a top plan view; and,

FIG. 7 is a bottom plan view.

The broken lines in FIGS. 1-7 are for illustrative purposes only and form no part of the claimed design.
